UNITED STATES PATENT OFFICE.

THOMAS LLOYD, OF BOSTON, MASSACHUSETTS.

DESIGN FOR A FOUNTAIN.

48,753.

Specification for Design.

Patented Mar. 21, 1916.

Application filed September 15, 1915. Serial No. 50,900. Term of patent 14 years.

To all whom it may concern:

Be it known that I, THOMAS LLOYD, a citizen of the United States, and a resident of Boston, in the county of Suffolk and State of Massachusetts, have invented a new, original, and ornamental Design for a Fountain, of which the following is a specification, reference being had to the accompanying drawing, forming part thereof.

The figure is a perspective view showing my new design.

A fountain designed as illustrated comprises an upright tank having flat faces, the height of the tank being greater than the

width and the width being greater than the depth from front to rear, but tapering toward the base. It also comprises a base having a circular flaring front flange and an arc-shaped arch spanning the rear portion of the base and secured to the front portion of the tank.

I claim:—

The ornamental design for a fountain, as shown and described.

THOMAS LLOYD.
